UNITED STATES PATENT OFFICE.

WINFIELD SCOTT MORRISON, OF OAKLAND, CALIFORNIA.

MACHINE FOR CLOSING COLLAPSIBLE TUBES AND APPLYING KEYS THERETO.

No. 920,609.

Specification of Letters Patent.

Patented May 4, 1909.

Application filed May 8, 1908. Serial No. 431,654.

To all whom it may concern:

Be it known that I, WINFIELD SCOTT MORRISON, a citizen of the United States, residing at Oakland, in the county of Alameda and 5 State of California, have invented a new and useful Machine for Closing Collapsible Tubes and Applying Keys Thereto, of which the following is a specification.

This invention relates to metal founding and 10 has a special reference to a machine for closing collapsible tubes and applying keys thereto.

One object of the invention is to provide an improved general construction of such a 15 machine.

Another object of the invention is to provide an improved operating mechanism for the dies in such a machine.

A third object of the invention is to provide 20 an improved form of pump and pump operating mechanism in a machine of this character.

The invention consists in a table or frame 25 whereon is mounted a melting pot, a thermostatically regulated gas burner, a tube support, a pair of clamping and casting dies, a metal pump, and means for operating said dies and pump.

The invention further consists in certain 30 novel features of construction and combinations of parts, hereinafter fully described, illustrated in the accompanying drawings, and specifically set forth in the claims.

In the accompanying drawings like characters of reference indicate like parts in the several views.

Figure 1 is a front elevation of a machine 40 constructed in accordance with this invention. Fig. 2 is a top plan view of such a machine. Fig. 3 is a right side elevation of such a machine. Fig. 4 is a horizontal section taken on the line A—A of Fig. 1. Fig. 5 is a vertical section taken on the line B—B of Fig. 1. Fig. 6 is a perspective view of the 45 front die and parts attached thereto. Fig. 7 is a similar view of the rear die. Fig. 8 is a cross section through the front and rear dies. Fig. 9 is a view of the dies, die levers and operating cams therefor. Fig. 10 is a view 50 arranged to show the cam groove in the cam which operates the rear die. Fig. 11 is a view of the pump cam and pump levers.

In the present embodiment of the invention the numeral 10 indicates the base or 55 table of the device. Upon this base or table is a pair of standards 11 having a cross bar

12 therebetween. Bearings 13 are formed at the upper end of these standards and receive a cam shaft 14. A belt pulley 15 is rotatably mounted on the shaft and has attached 60 thereto a clutch member 16. A clutch member 17 is rigidly keyed to the shaft 14. The clutch members 16 and 17 may be of any preferred form and it is not deemed necessary to illustrate or describe in the present 65 invention any specific form of such device. It will be preferable, however, to use some form of clutch which automatically disengages after one revolution of the shaft.

Mounted upon the bar 12 is a bracket 18 70 which carries a melting pot 19. The bracket 18 is provided with a rearwardly and upwardly extending arm 20 having a pump lever 21 pivotally attached thereto. Within the melting pot 19 is formed a pump cylinder 75 22 open at the top and further provided with a lateral opening 23 extending inwardly to afford communication with the metal contained in the melting pot. A pump rod guide 24 is formed at the upper end of the 80 melting pot and a pump rod 25 having a piston head 26 lies within the pump cylinder and the pump rod guide. Collars 27 are fixedly mounted on the pump rod 25 and the end of the pump lever is forked as shown at 85 28 so as to embrace the pump rod 25 and lie between the collars 27. Rigidly secured to the melting pot 19 is a rod 29 which passes through a lug 30 on the pump lever 21. Mounted on the rod 29 is a collar 31 and between that collar and the lug 30 is held a 90 spring 32 which normally tends to force the pump rod down. Keyed upon the shaft 14 so as to rotate therewith is a cam 33. Mounted upon the pump lever 21 is a roller 34 95 which presses against the cam 33. It will thus be seen that with every revolution of the shaft 14 the pump piston will be raised by the action of the cam 33 and depressed by the action of the spring 32. The exterior 100 portion of the melting pot 19 is flattened opposite the lower end of the pump cylinder, and is provided with a recess 35 wherein is mounted a bushing 36, preferably of hardened steel having an opening 37 thereto. An 105 opening 38 is formed in the wall of the pump cylinder and communicates with the opening 37. Axially coincident with the opening 38 but in the opposite wall of the pump cylinder is an opening 39. A gland 40 is formed 110 in the wall of the melting pot 19 at a point opposite to and axially coincident with the

openings 39 and 38. A valve stem 41 passes through the gland 40 and is adapted to lie within the openings 39 and 38, and form a closure for the opening 37. An operating handle 42 is attached to the valve stem. Suitable plugs 43 are provided at the lower end of the melting pot and pump cylinder.

Mounted upon a short shaft 44 rigidly attached to the melting pot are levers 45 and 46, bell-crank type. The levers 45 and 46 are provided at their lower ends with jaws adjusted to receive die blocks 48. The die blocks 48 are hollow interiorly to provide a passage for a circulating cooling medium, in the present case water. For this purpose there is provided suitable pipe connection 49 and a supply pipe 50 having suitable valves therein. The die blocks 48 are so arranged that when in contact the upper portion and one end of the lower portion will press against similar portions on the opposite die, as shown at 51. A half mold of the key desired to be formed is made in each of the die blocks as indicated at 52. Immediately below the shank of the key the opposed faces of the die blocks are spaced as at 53 for a short distance and are then beveled or outwardly flared as at 54. This construction can best be observed in Fig. 8. The die blocks 48 are further provided with a lug 55 and when the dies are in contact these lugs form a runner block having each one-half of a runner as at 56 formed therein.

In order to provide a means for pressing the die blocks firmly against the melting pot during the operation of said means, there is mounted on the melting pot a pin 57 having a bar 58 slidably mounted thereon, but secured from rotation by any desired means. On the outer end of the pin 57 is a threaded portion 59 whereon is mounted a washer 60 and nut 61. A spring 62 is also mounted on the pin 57 and lies between the bar 58 and the washer 60. Each of the levers 45 and 46 is provided with a lug 63. The faces of the lugs are arranged to lie in the same plane and are in contact with the bar 58. By means of the nut 59 the spring 62 may be tensioned to the required degree and will cause the bar 58 to force the die blocks firmly against the flattened portion of the melting pot 19.

Mounted upon the shaft 14 to rotate therewith is a cam 64 provided with a cam groove 65 adapted to receive a roller 66, which is supported on the lever 45. There is also mounted on the shaft 14 and fixedly attached thereto a second cam 67 provided with a cam groove 68 arranged to receive a roller 69 carried on the lever 46. A gas burner 70 preferably of the Bunsen type is supported beneath the melting pot 19 and passes upward through an opening 71 in the base 10. The burner 70 is supplied with gas from a suitable pipe 72 which is provided with valves 73 and 74. A cover 75 is

provided for a portion of the top of the melting pot and attached to this cover is thermostat stand 76. A pipe 77 branches from the pipe 72 between the valves 73 and 74 and extends to a thermostatically controlled valve indicated at 78. A pipe 79 leads from the thermostatically controlled valve to a point beyond the valve 74 and there is thus formed a by pass extending around said valve, the flow of gas therethrough being thermostatically controlled.

A screen 80 surrounds the upper end of the burner 70 and is here shown as provided with a series of perforations 81 to permit the passage of the heated gases therethrough. Surrounding and spaced from the screen 80 and the melting pot 19 is a casing 82 which is supported on suitable lugs formed on the melting pot. A cover 83 closes that portion of the melting pot not covered by the cover 75 and is provided with means to remove the same from the melting pot. This cover 83 may if desired be hinged either to the melting pot or the fixed portion of the cover 75. When the cover is closed the space around the melting pot between that and the casing 82 is closed in at the top. In order to provide for the escape of the gases a chimney 84 is mounted on the casing 82 and communicates with the space between casing and the melting pot.

In order to actuate the clutch there is provided on that one of the standards 11 which is nearest the clutch a lug 85 whereon is pivotally mounted a bell-crank lever 86 one arm of which is attached to the clutch as shown in Fig. 1, and the other arm of which extends across the machine and is connected to a treadle rod 87, which in turn extends downward to a suitable foot treadle not deemed necessary here to be shown. Attached to the bell-crank lever 86 and to the frame of the device is a spring 88 normally throwing the clutch out of engagement.

Upon the base of the machine is mounted a boss 89 having an upwardly extending pin 90 thereon. Upon the pin 90 is mounted a sleeve 91 provided at its upper end with a laterally extending bifurcated arm 92, the inner side of the bifurcated portion being shaped to receive the cap and neck of a collapsible tube. This tube is indicated by heavy dotted lines in several of the views as at 93.

In order to provide for the casting of various sizes of keys on different styles and sizes of collapsible tubes the die blocks 48 are detachably secured to the jaws 47 by means of set screws 94 and the sleeve 91 is made in a variety of lengths and proportioned so that any sizes of collapsible tubes may be held therein.

As it is desirable to know at all times the temperature of the molten metal in the melting pot there is provided a thermometer

95 attached to the cover 75 and extending downward therethrough. This thermometer is preferably metal incased in order to prevent damage thereto.

5 The operation of the device will now be described. The first step to be accomplished is the melting of an alloy suitable for forming the closure and key. The solid alloy, preferably broken into small pieces is placed in the 10 melting pot in the desired quantity. The valves 73 and 74 are then opened and the burner 70 lighted. With the burner and pipe properly proportioned to the size of the melting pot and the valves opened in this manner, 15 the contents of the pot are quickly melted. When the molten metal has reached the required temperature, that is to say that temperature at which it is found by practice that the alloy forms the best casting, the valve 74 20 is closed and the thermostatic valve is adjusted to regulate the flow of gas through the by pass pipes 77 and 79 and maintain the molten bath at this temperature. The machine now being ready for work; a previously 25 filled tube, flattened at one end so that the edges of the flattened end are in close contact, is placed up side down in the holder 92 and with the flattened edges in contact with the portion 53 of the rear die 48. The treadle 30 is then depressed, (it being assumed that the belt pulley 15 is in motion), and the clutch actuated to put the shaft 14 with various cams thereon in motion. During the first 35 part of the rotation of the shaft and cams the lever 46, and consequently the rear die blocks 48 remain stationary while the lever 45 with the front die blocks 48 is closed in thereon and the flattened end of the tube is thus securely clamped between the front and 40 rear die blocks. As soon as this is accomplished the levers 45 and 46 move synchronously as a unit toward the rear of the machine until the runner 56 is brought opposite the opening 37. By means of circular portions 45 of the cam grooves, lateral motion of the die blocks now stop. Meanwhile, by the action of the pump cam the pump piston 26 has been raised so as to let sufficient metal for one casting pass through the opening 23 50 and into the lower part of the pump cylinder 22. As the die blocks come to rest the roller 34 is at its highest point and immediately thereafter the lifting action of the cam 33 ceases. The spring 32 now presses the piston 55 26 downward and there is ejected sufficient metal to form the closure and the key. The levers 45 and 46 are now caused to move synchronously forward thus cutting off the sprue formed in the opening 37 and closing said 60 opening. As soon as this has been accomplished the lever 46 comes to rest while the lever 45 continues to open until the parts again assume the position in which they were at the time of starting and which is shown in 65 Fig. 9. As stated previously, it is preferable

to use a clutch which will stop at the end of the cycle of movement, but it is to be understood that if the foot is put upon the treadle the clutch will continue to operate and the collapsible tubes may thus be continuously 70 sealed and provided with keys.

Should it at any time be deemed advisable to change the die while there is molten metal in the pot 19, all that is necessary to do is to slightly raise the pump piston 26 and screw 75 in the valve stem 41. The end of this stem will then act as a valve to close the opening 37 and the die blocks may be changed without danger of loss of metal through that opening and the consequent injury of the operator. When the change has been effected 80 the opening 37 may again be freed and the operation continued with the new die blocks.

When it is desired to draw off the molten metal remaining in the pot 19, the plug 43 85 under that pot is removed and the metal allowed to flow out of the opening thus left. In like manner the pump cylinder 22 can be cleared of the molten metal therein contained.

It is obvious that many minor changes 90 may be made in the form and proportion of the pot of this device without departing from the principles thereof. It is not, therefore, desired to confine the invention to the exact form and proportion herein set forth but it 95 is desired to include all such as properly come within the scope of the invention.

Having thus described the invention what is claimed as new and desired to be secured by Letters-Patent is:—

1. A tube support, oppositely disposed pivoted tube crushing dies coöperating to constitute a mold, and means for simultaneously actuating said dies.

2. A tube support, opposed pivoted tube 105 crushing dies coöperating to constitute a mold, a revoluble shaft, and means upon the shaft for positively engaging the dies to simultaneously actuate them.

3. A tube support, oppositely disposed 110 pivotally supported tube crushing dies, said dies coöperating to constitute a mold, means for actuating the dies to crush the tube and for maintaining the dies together for a predetermined period, and means for directing 115 molten metal into the dies during their period of rest.

4. A tube support, opposed pivotally mounted dies adjacent thereto for crushing one end of a tube mounted on the support, 120 means for simultaneously actuating the dies to crush the tube and for maintaining said dies together for a predetermined period, said dies coöperating to form a key mold, a melting pot having an outlet, means for 125 shifting the dies into register with the outlet while closed together, and means for directing a molten metal into the dies from said outlet.

5. A tube support, opposed pivotally sup- 130

ported dies for crushing one end of a tube mounted on the support, means for bringing the dies together to crush the tube, said dies coöperating to constitute a key mold, a melting pot, means for shifting the contacting dies into communication with the melting pot, and means for forcing a molten metal into the dies.

6. A tube support, levers adjacent thereto, 10 opposed dies carried by the respective levers, means for actuating the levers to crush one end portion of the supported tube between the dies, said dies coöperating to constitute a key mold, a melting pot, means for bodily 15 shifting the levers and dies laterally to place the dies in communication with the melting pot, and means for forcing molten metal from said pot and into the dies.

7. A tube support, levers mounted for 20 oscillation adjacent thereto, a die carried by each lever, said dies being oppositely disposed, means for actuating the levers to bring the dies together and crush a portion of the tube, said dies coöperating to constitute a key mold, and mechanically controlled means for directing molten metal into the dies.

8. A tube support, levers adjacent thereto, a die detachably mounted upon each lever, 30 said dies being oppositely disposed, means for actuating the levers to crush a portion of a supported tube between the dies, said dies coöperating to constitute a key mold, means for directing molten metal into the dies.

35 9. A tube support, dies mounted for oscillation adjacent thereto, means for actuating the dies to crush a portion of a supported tube, said dies coöperating to constitute a key mold, a melting pot having an outlet, 40 means for shifting the dies into communication with the outlet, and means for forcing molten metal through the outlet and into the dies.

10. A tube support, detachably supported 45 dies mounted for oscillation adjacent thereto, means for actuating the dies to crush a portion of the supported tube, said dies coöperating to constitute a key mold, and means for directing a cooling medium into 50 each die.

11. A tube support, a melting pot having a valved outlet, means for forcing molten metal through the outlet, levers mounted for oscillation adjacent the outlet and above 55 the tube support, dies carried by the levers and oppositely disposed, means for actuating the levers to crush a portion of the supported tube between the dies, said dies coöperating to constitute a key mold, and 60 spring-pressed means for shifting the dies and levers laterally to bring the dies in position to receive molten metal from the outlet.

12. In a device of the character described, a tube support, a two part die adapted to 65 clamp the flattened end of a tube, means to

force molten metal maintained at a definite temperature into said die, levers supporting the parts of said die, a rotatable cam shaft, cams carried thereon, cam rollers mounted on said levers to coact with said cams, said 70 levers and cams constituting an opening and closing mechanism for said die.

13. In a device of the kind described, a tube support, a two part die provided with a key mold therein and adapted to clamp the 75 flattened end of a tube and hold the same in the shank portion of said key mold, means to force molten metal maintained at a definite temperature into said die and simultaneously close said tube and cast a key thereon, levers provided with jaws to receive the parts of said die, fastening means mounted on said jaws to detachably secure the parts of said die therein, a rotatably mounted cam shaft, cams mounted thereon, and rollers 85 mounted on said levers and adapted to coact with said cams and open and close said die.

14. In a device of the character described, a tube support, a two part die provided with 90 a key mold therein and runner therefrom, and adapted to clamp the flattened end of a tube and hold the same in shank portion of said key mold, means to pour molten metal 95 into said key mold and simultaneously close said tube and cast a key therein, comprising a metal melting pot, means coacting therewith to maintain the molten metal at a fixed temperature, a pump cylinder formed therein, provided with an opening leading therefrom and adapted to register with the runner of said die, a pump piston held in said cylinder, a piston rod attached to said piston, a cam shaft, means to rotate said cam shaft, a cam mounted on said shaft to rotate therewith, a cam lever actuated by said cam and adapted to actuate said piston rod, levers supporting the parts of said die, and means for actuating said levers to open and close 100 said die.

15. In a device of the character described, a tube support, a two part die provided with a key mold therein and a runner therefrom, and adapted to clamp the flattened end of a tube and hold the same in the shank portion 105 of said key mold, means to pour molten metal into said key mold and simultaneously close said tube and cast a key thereon, comprising a metal melting pot, means coacting therewith to maintain the molten metal at a fixed temperature, a pump cylinder formed therein provided with an opening leading therefrom, a pump piston held in said cylinder, a piston rod connected to 110 said piston, a cam shaft, means for rotating said cam shaft, a cam mounted on said cam shaft and adapted to actuate said pump piston rod, levers provided with jaws adapted to receive the parts of said die, the jaws having securing means adapted to detach- 115 120 125 130

ably attach parts of said die thereto, other cams mounted on said shaft, and rollers on said levers adapted to engage said cams to open and to close said die and move the same into and out of registering position with the opening from said pump cylinder.

In testimony that I claim the foregoing as

my own, I have hereto affixed my signature in the presence of two witnesses.

WINFIELD SCOTT MORRISON.
